UNITED STATES PATENT OFFICE.

DAVID LEE RUSH, OF HAZLEHURST, MISSISSIPPI.

WHEEL.

SPECIFICATION forming part of Letters Patent No. 394,511, dated December 11, 1888.

Application filed March 20, 1888. Serial No. 267,868. (No model.)

To all whom it may concern:

Be it known that I, DAVID LEE RUSH, a citizen of the United States, residing at Hazlehurst, in the county of Copiah and State of Mississippi, have invented certain new and useful Improvements in Hubs for Fastening Tires and Filling Wheels; and I do declare the following to be a full, clear, and exact description of the invention, such as will enable others skilled in the art to which it appertains to make and use the same.

This invention has relation to improvements in wheel-hubs; and it has for its object to provide a hub capable of tightening the spokes, and consequently the tire and felly, without the necessity of disconnecting any of the parts, and at the same time producing a strong and durable wheel. These objects are accomplished by the means shown and illustrated in the accompanying drawings, in which—

Figure 1 is a transverse vertical sectional view of a wheel-hub constructed according to my invention, the parts being all shown in a position to receive the spokes. Fig. 2 is an elevation of the inner side of one of the hub-sections, showing the cone in position on the tubular box. Fig. 3 is a view of the cone removed, and Fig. 4 is a view of one of the movable wedges.

Referring by letter to the said drawings, A indicates the inner and B the outer hub-sections, which together constitute the main portion of the hub. These sections are designed to be placed upon a tubular box, C, which is externally threaded for the greater portion of its length.

The outer section, B, has its inner end provided with an annular vertical flange, a, and directly beneath this flange an annular recess, b, which latter communicates with an annular recess, c, of much less circular area. The flange a of the section B is provided on its inner side with lugs d, which extend down in a tapering triangular form into the recesses b and c, and are designed to co-operate with similar lugs, e, on the adjacent face of the section A in forming sockets for the inner ends of the spokes.

The inner section, A, is provided with an internal annular recess, f, conforming to the recess b in the section B, for the purpose of

receiving wedges, forming seats for the spokes, as will be hereinafter more fully referred to.

The tubular box C terminates at its outer end in an enlargement, g, recessed, as shown, and having internal threads, h, the recess being designed to receive the nut usually employed on the end of the axle-spindle.

E indicates a cap for the outer end of the hub. This cap has an externally-threaded portion, i, designed to engage the threads h on the end g of the box, and the said cap is hollow to receive the spindle-nut. The box C is also provided with an annular groove, k, which is designed to receive the inner end of a threaded rod or screw, F, which passes through an aperture in the hub-section B, so that the said section may be limited in its movements or fixed longitudinally to the box C.

It will be observed that the box C extends a sufficient distance at its inner end beyond the hub-section A to receive a nut, G. By this construction it will be seen that by simply turning this nut in one direction the hub-section A may be moved in the direction of the section B, while by reversing the movement of the nuts the sections may be allowed to separate.

H indicates a cone provided with a central internally-threaded bore, as more fully shown in Fig. 1 of the drawings. This cone is grooved longitudinally on its external surface, as shown at l, to receive the tapered inner ends or edges of the lugs d in the hub-sections, and these grooves l increase in depth and width from the small end to the large end of the cone, the plain portions m, formed by the grooves l, furnishing seats for the wedges I, which seat the inner ends of the spokes. It will thus be seen that when the hub-sections have been slipped upon the cone, so as to bring the inner edges of the lugs d into grooves l of the cone, one will be prevented from turning without the other. By having these lugs d enter the grooves l of the cone H it will also be seen that the wedges I will be kept in their proper relative positions while being moved upon the plain portions m of the cone.

The wedges I have bevel or inclined sides n, which engage the plain portions m of the cone, and the opposite sides of these wedges are provided about midway of their length

with a transverse recess, *r*. In practice these wedges are placed within the annular recesses *f* and *b* of the respective hub-sections and upon the plain portions *m* of the cone, so that 5 the recesses *r* of the said wedges will lie at the base of the spoke-sockets.

By a hub of this construction the tire and felly of a wheel may be tightened without the necessity of removing either of them, it being 10 simply necessary to turn the parts so as to move the wedges up the inclined surfaces of the cone.

The hub-section *A* is provided adjacent to the socket-lugs with an externally-threaded 15 portion, *s*, which is designed to receive an internally-threaded band, *t*, so that when it is desirable to secure the two hub-sections together by means of bolts, which may be passed through apertures *T*, the band *t* may be turned 20 up and prevent the said bolts or their nuts from casual displacement.

Having described my invention, what I claim is—

1. In a hub, the combination, with the externally-threaded box, of the hub-sections re- 25

cessed, as described, and provided with the tapering lugs on their adjacent faces to form spoke-sockets, the internally-threaded cone having external grooves to receive the inner edges of the socket-lugs, and wedges having 30 spoke-sockets and arranged upon the said cone, substantially as specified.

2. In a hub, the combination, with the externally-threaded box, of the hub-sections recessed, as described, and provided with the 35 socket-lugs, the internally-threaded cone arranged upon the said box and having grooves on its outer side to receive the inner edges of the socket-lugs, the wedges arranged upon the inclined surface of the cone and having spoke- 40 sockets, the inner end of the threaded box being extended to receive a nut whereby the section *A* of the hub may be moved upon the said box, substantially as specified.

In testimony whereof I affix my signature in 45 presence of two witnesses.

DAVID LEE RUSH.
